UNITED STATES PATENT OFFICE.

ARTHUR P. SANBORN AND ROY C. WILSON, OF OSSINING, NEW YORK.

CLOSED-CIRCUIT MAGNET.

1,195,506.

Specification of Letters Patent. Patented Aug. 22, 1916.

Application filed July 22, 1915. Serial No. 41,382.

To all whom it may concern:

Be it known that we, ARTHUR P. SANBORN and ROY C. WILSON, citizens of the United States, residing at Ossining, in the county 5 of Westchester and State of New York, have invented certain new and useful Improvements in Closed-Circuit Magnets; and we do declare the following to be a full, clear, and exact description of the invention, 10 such as will enable others skilled in the art to which it appertains to make and use the same.

This invention relates generically to means for arresting the travel of a locomotive or 15 train along the right of way.

One object of the invention is to provide an electric magnet adapted to be controlled by the operating circuit of a standard semaphore and movable thereby to operative and 20 inoperative positions dependent upon the dispositions of the semaphore arm.

Another and further object is to provide an electrically controlled means, motor or solenoid for actuating said electro-magnet, 25 said means or solenoid having its energizing circuit normally closed, whereby opening of said circuit will permit the electro-magnet to revolve to an operative position.

Another and further object resides in providing a means for augmenting the strength 30 of the electro-magnet when the latter is in an operative position.

With these and other objects in view our invention consists of certain novel details 35 of construction, combination and arrangement of parts to be hereinafter more particularly set forth and claimed.

In the accompanying drawings, in which corresponding parts are indicated by similar 40 reference characters: Figure 1 is a diagrammatic view illustrating the disposition of our improved track magnet and showing the circuits established when the semaphore arm is in a position indicating safety; Fig. 2 is a 45 longitudinal section through the casing of our improved track magnet having in connection therewith a diagrammatic illustration of a circuit established when the semaphore arm is in a position indicating danger; Fig. 3 is a transverse vertical section 50 taken on the line 3-3 of Fig. 2, with the magnet in operative position; Fig. 4 is a similar view taken on the line 4-4 of Fig. 2; Fig. 5 is a similar view with the magnet 55 in inoperative position, and taken on the line 3-3 of Fig. 2.

Briefly stated our invention consists of a casing adapted to be disposed adjacent the track at the entrance of each block, said casing having therein a permanent magnet, the latter having two positions operative and inoperative. A motor within the casing normally maintains the electro-magnet in an inoperative position. When, however, the circuit of said motor is broken the permanent magnet will be revolved by gravity to an operative position and when in this position the energizing coil which is carried by the permanent magnet is placed in circuit with a source of electrical supply so that the strength of the permanent magnet when in operative position is thereby materially increased.

Referring more particularly to the drawings 1 represents a locomotive, 2 the track rails, and 3 a semaphore having an electrically controlled arm 4. Within the base of the semaphore 3 is a motor 5 which controls the movement of arm 4 in a manner readily understood by those versed in the art. Also mounted within the base of semaphore 3 is an electro-magnet 6 which co-operates with switch 7, said switch having two terminals 8 and 9 and being adapted to close one break in the circuit of battery 10 in a manner hereinafter to be pointed out.

Situated adjacent the tracks 2 at the entrance of each block is a metal casing 11 rectangular in configuration and preferably formed of aluminum. However, in this connection it is to be understood that we do not wish ourselves to be limited in any way to the use of this particular metal. A cover 12 forms a closure for the open top of the casing, said cover being, when in closed position, secured by any suitable fastening element.

Suitably mounted in spaced and alining relation within the casing 11 are the two standards 14. Sleeves 15 secured to the upper end of the standards 14 contain externally threaded pivot pins 16 which are held in fixed position by the lock nuts 17. The inner ends of the pivot pins 16 are pronged for a purpose hereinafter to be set forth.

A permanent magnet in the form of a U-shaped bar 18, the latter including an intermediate portion 19 and legs 20 the free extremities of which are T-shaped as at 21, is pivotally supported intermediate the standards 14. Trunnions 22 formed on the legs 20 are provided with indentations to receive

- the pronged ends of the pivot pins 16 to pivotally support the magnet as will be readily understood without further description.
- 5 A quadrant gear 23 is fixedly secured to one of the trunnions 22 and meshes with gear 24 keyed to the shaft of motor 25. This motor 25 is supported in proper position by bracket 26 fastened to standard 14.
- 10 Metallic disks 26' and 26'' fixed to the remaining trunnion 22 are provided on their periphery with short strips of insulating material the purpose of which will be hereinafter set forth.
- 15 Two resilient fingers 27 are so mounted within the casing 11 as to have their upper extremities in engagement with the peripheries of the disks 26' and 26'', the lower extremities of said fingers being secured in insulated relation to terminal block 28 within the casing. This terminal block 28 has the two binding posts 29 and 29' thereon which latter are connected to the resilient fingers 27. Counterweights 30 projecting in spaced relation from the intermediate portion 19 of the permanent magnet serve to bring the legs 20 to a vertical or operative position. When the legs 20 are in a horizontal position the T-shaped enlargements thereon will be disposed immediately to the rear of one side of the casing 11, (which is the inoperative position of the same,) and as the movable member on the locomotive is arranged to pass above the top of the casing 35 it will at once be obvious, that, when in the position above referred to, the magnet will be inoperative. A magnetizing coil 31 encompasses the intermediate portion 19 of the permanent magnet, the extremities of said coil being connected to the disks 26' and 26'' respectively. To energize motor 25 so that the latter may actuate legs 20 of the permanent magnet to a horizontal position, said motor is connected as follows to the 40 distant circuit which controls the operating motor of the semaphore. The positive lead 32 from the distant circuit is connected to one brush of motor 5 in the base of semaphore 3, the other brush thereof being connected by a conductor to one terminal of the electric magnet 6. The other terminal of this magnet is connected by a conductor 33 to one terminal of motor 25. The other terminal of said motor is connected by a 45 conductor 34 to the negative lead 35 of the distant circuit. From the circuit traced it will be obvious that motors 5 and 25 are energized simultaneously so that as long as the semaphore arm 4 is maintained in positions indicative of safety or caution, motor 25 will be energized so as to retain the arms 20 of the magnet in a horizontal position.
- 50 To increase the strength of the magnet when the latter is in a vertical position coil

31 thereon is placed in circuit with battery 10 as follows: The positive pole of said battery 10 is connected by a conductor 36 to one terminal 9 of switch 7. The other terminal 8 thereof is connected by a conductor 37 to one of the binding posts 29 on the terminal block 28, the remaining binding post 29' being connected by a conductor 38 to conductor 34 which conductor is connected by a conductor 39 to the negative pole of battery 10. As it would not be desirable to have the current continuously pass through the coil 31 on the permanent magnet when the same is in a horizontal position, the insulating material on the two 70 disks 26' and 26'' is so arranged as to be in engagement with resilient fingers 27 when the magnet is in an inoperative position so as to break the circuit of battery 10.

In view of the above it will be obvious 85 that the passage of current through motor 5 to energize the latter and maintain the semaphore arm 4 in position indicative of caution or safety, will also energize motor 25 and retain the permanent magnet in inoperative position, while on the other hand when the circuit of the motor 5 is broken to allow the semaphore arm 4 to drop to a position indicating danger, that of motor 25 will also be broken so as to allow the permanent magnet to revolve to an operative position with the enlargement 21 disposed immediately below the hinged cover of casing 11. Opening the circuits of motors 5 and 25 respectively also deenergizes the 90 electro-magnet 6 and permits switch 7 to close one break in the circuit of battery 10, the other break in said circuit being closed by the resilient fingers 27 which, when the permanent magnet is in a vertical position, 95 engage the periphery of the metallic disks 26' and 26'' so that current may thus pass through the coil 31 on the permanent magnet to further magnetize the latter.

When the permanent magnet is in an operative position the magnetic lines of force 100 may pass to the exterior of the casing through the cover thereof and thus pull downwardly the movable arm carried by the locomotive, which as the latter passes 105 casing 11, projects above the same. This arm when actuated may co-operate with suitable circuit closing members to close certain circuits on the locomotive and in this manner arrest the travel of the latter and 110 warn the engineer that he is passing a semaphore whose arm indicates danger. Inasmuch as it is immaterial to this invention what result movement of the arm produces, the same is only shown for the purpose of 115 disclosing the utility of the invention under consideration. Therefore the circuits for controlling the mechanism which might operate the air valve of the train and control the movement of the latter as well as 120 125 130

the switches which would be affected by movement of the arm, are omitted.

Although in the description and illustrated embodiment of our invention we have shown a motor as a means for actuating the permanent magnet nevertheless it is to be understood any other suitable means may be substituted for the motor. As hereinbefore described, the magnet 19 is a permanent magnet, the material from which it is made being hard steel, which, as is well known, retains its magnetism. As the batteries which supply the source of current for the circuit may at times deteriorate and as the wires in the coil or in the circuit may become broken, this construction provides a device which will be operative at all times. By the provision of a magnet which is normally maintained in an inoperative position by a motor whose circuit is normally closed should the circuit of said motor be opened the electro-magnet will drop to an operative position and consequently should the semaphore system be disarranged for any reason the electro-magnets controlled by such semaphore would not remain inoperative, but would immediately drop to operative position so as to arrest the travel of the train or locomotive as the case may be.

Although by the foregoing we have set forth certain elements as best adapted to perform the functions allotted to them, it is to be understood that certain minor changes as to form, substance, etc., may be resorted to within the scope of the appended claims.

Having now described our invention, what we claim is:—

1. In an electro-magnet tripping mechanism of the character described, the combination with a swivelly mounted permanent magnet disposed adjacent a track, of means for operating said magnet to horizontal and vertical positions, and additional means for increasing the magnetic strength of said permanent magnet when the latter is in a vertical position.

2. In an electro-magnet tripping mechanism of the character described, the combination with a permanent magnet disposed contiguous to a track, and a source of electrical supply; of means for actuating said magnet to operative and inoperative positions, an energizing coil carried by said magnet, and additional means for placing said coil in circuit with said source of supply when the magnet is in its operative position.

3. In an electro-magnetic tripping mechanism of the character described, the combination with a pair of standards arranged in spaced relation adjacent a track, and a permanent magnet swivelly supported by said standards; of means for actuating said magnet to horizontal and vertical positions, a

source of electrical supply, an energizing coil carried by said magnet to increase the strength thereof, a pair of metallic disks carried by said magnet and connected to the extremities of the coil thereon, and a pair of contact members adapted to cooperate with said metallic disks and place said coil in circuit with said source of supply.

4. In an electro-magnetic tripping mechanism of the character described, the combination with a pair of standards disposed in spaced relation adjacent a track, and a U-shaped magnet swivelly supported by said standards and having operative and inoperative positions; of a motor, a quadrant gear carried by said motor, a quadrant gear carried by said magnet and meshing with said motor gear, means for energizing and de-energizing said motor, a coil encircling the intermediate portion of said U-shaped magnet, a source of supply, and means for placing said coil in circuit with said source of supply when the magnet is in an operative position.

5. The combination with a casing; of a U-shaped magnet swivelly mounted within the casing and having horizontal and vertical positions, means for bringing said magnet to horizontal and vertical positions, a coil disposed upon the intermediate portion of said U-shaped magnet, a source of electrical energy, and means for placing said coil in circuit with said source of electrical energy when the magnet is in a vertical position.

6. The combination with a casing, of a pair of standards disposed in spaced relation within said casing, a U-shaped permanent magnet swivelly supported by said standards, said magnet having horizontal and vertical positions, enlargements on the extremities of said U-shaped magnet adapted to be disposed to the rear of one side of said casing when said magnet is in a horizontal position, a motor co-operating with said magnet to actuate the latter to a horizontal position, an energizing circuit for said motor, a coil disposed upon the intermediate portion of said U-shaped magnet, a source of supply, means to place said coil in circuit with said source of supply when said magnet is in a vertical position, and additional means for disconnecting said coil from said source of supply when said magnet is in a horizontal position substantially as and for the purpose set forth.

In testimony whereof we have hereunto set our hands in presence of two subscribing witnesses.
